MEANS FOR COATING THREAD

George C. Davis, Jr., Gastonia, N. C., assignor to
 Threads, Incorporated, Gastonia, N. C., a corporation of North Carolina

Application July 25, 1941, Serial No. 404,009

5 Claims. (Cl. 91—40)

This invention relates to means for treating yarn or thread and more especially to the art of applying a treating solution such as wax, paraffin, size and the like thereto while in a softened state. It is necessary to apply many types of material to threads while in a liquid or softened state due to the inherent qualities of the material, and also to obtain a more uniform distribution. For example, wax or paraffin has a low melting point slightly above normal temperatures. When it is desired to apply this material to thread, it is desirable to subject it to heat in order to reduce it to a liquid or softened state, so that a more uniform application to the thread can be obtained.

The conventional means of application of some of the above-named treating solutions while in a liquid state, such as sizing, however, has many disadvantages. The liquified material penetrates the thread and tends to set the fibers in whatever positions they happen to occupy. Many treating materials quickly harden or congeal on the thread into a cake-like structure, thus leaving an unpolished or uneven yarn. Experience has proven that a uniform distribution of liquified treating material on the thread has been very difficult to obtain by merely immersing the thread or passing the same in contact with an application roll. The projecting fibers at one point on the strand will often collect more treating solution from the roll than at the other points, resulting in a lack of uniformity as to the size of the thread.

It is therefore an object of this invention to provide an apparatus for applying treating solution to thread comprising a rotating brush over which the thread is passed, in combination with means such as a partially immersed roll, for applying the solution to the brush, whereby the solution is transferred from the brush to the thread. Means are also provided for automatically removing the thread out of contact with the brush when the thread is caused to cease traveling, thereby preventing an excess amount of material from hardening at the contacting points.

Some of the objects of the invention having been stated, other objects will appear as the description proceeds, when taken in connection with the accompanying drawings, in which—

Figure 1 is a front elevation of a portion of a winding machine showing my improved attachment for treating thread associated therewith;

Figure 2 is a vertical sectional view taken along the line 2—2 in Figure 1;

Figure 3 is an isometric schematic view illustrating a conventional driving means for the winder spindle;

Figure 4 is a vertical sectional view similar to Figure 2, illustrating a slightly modified form of the invention.

Winding head structure

Referring more particularly to the drawings, the numeral 10 denotes a conventional winder frame having mounted thereon a plurality of winder heads 11. Each of the winder heads has a spindle shaft 12 upon which a package of thread is adapted to be wound. This shaft has a suitable pulley 16 fixedly secured on one end thereof (Figure 3) and this pulley is adapted to be driven by frictional contact with a suitable belt 17, said belt normally having insufficient frictional contact with the periphery of wheel 16 to rotate the same when the winding mechanism is not in operation.

The belt 17 is adapted to be pressed into engagement with the periphery of wheel 16 during a winding operation by means of a suitable tightener pulley 18, which pulley is rotatably mounted on the free end of lever 19 pivoted as at 20. In order to hold the pulley 18 out of contact with the belt 17 and thus prevent sufficient friction between the belt 17 and the spindle pulley 16 to drive the spindle, a suitable lever 21 is provided. The upper end of the lever 21 supports the free end of lever 19 and the lower end of the lever 21 is fixedly secured upon a shaft 22, said shaft having fixedly secured on the other end thereof a suitable operating handle 23. When the lever 23 is rotated in a clockwise manner (Figures 1 and 3) pulley 18 will be permitted to fall upon the belt 17 to press it against the periphery of pulley 16. This engagement with the pulley will cause the spindle shaft 12 to rotate and thereby cause thread to be wound upon the package 14.

The package 14 is formed from suitable thread 27, said thread passing through an eyelet 28 and a tension mechanism 29 before it is wound upon the package. All of the above-described mechanism is conventional in winding machines, but it is deemed necessary to show and describe this much of the old structure in order to more clearly illustrate my improved method and means for treating thread.

A suitable elongated trough 30 is provided, said trough having a hollow receptacle 31 between its inner and outer walls, for the reception of a suitable heating agent such as steam or hot

water. The heating agent is admitted into the receptacle through a suitable pipe 32 and this pipe has its lower end connected to a suitable heated tank 33. From the heater 33 another pipe 34 leads to the outlet side of a pump 36, said pump having a second pipe 37 leading from its intake side. The other end of the pipe 37 is connected to the opposite end of the trough 31 from the end of which pipe 32 is connected. It is therefore seen that a circulating system for the heated agent is provided by members designated by reference characters 32 to 37 inclusive. The heating agent will be forced through the pipe 32 into the receptacle 31 and then expelled from this receptacle through pipe 37. In order to drain the heating agent from the receptacle 31, a suitable outlet pipe 39 is provided.

Treating solution container and roller

Rotatably mounted in the trough 30 is an elongated roller 40, said roller being preferably made of metal and having a shaft 41 extending therethrough which has one end thereof rotatably mounted in a bearing 42 and its other end rotatably mounted in a similar bearing 43. The roller 40 is fixed on shaft 41. The bearings 42 and 43 are supported by suitable upstanding brackets 44 and 45 respectively. The shaft 41 also has mounted thereon a pulley 47 which, in turn, has mounted thereon a belt 48, said belt being also mounted upon a second pulley 49 on a shaft 50, said shaft 50 extending from a gear reduction housing 51. Another shaft 52 extends from gear reduction housing 51 and this shaft is driven by a suitable source of power such as a motor 53. It is through the members 47 to 53 inclusive that the roller 40 is rotated.

By observing Figure 2 it will be seen that the roller 40 is adapted to be partially immersed in a bath of liquid material 55. This liquid material serves as a treating agent for the thread and may be of any suitable material such as wax, paraffin, sizing solution and the like, depending upon the type of treatment desired to give the yarn.

Applicator brush

The shaft 50 also has another pulley 60 fixed thereon upon which a belt 61 is mounted. The belt 61 is also mounted upon a pulley 62 on shaft 63, said shaft being rotatably mounted in upright brackets 64 and 65. Shaft 63 has fixedly secured thereon at spaced intervals suitable circular brushes 66. The periphery of each of the brushes 66 is adapted to contact the periphery of the roller 40 at a point where the same is not immersed in the solution 55. As the shaft 63 is rotated along with the roller 40, the peripheries of the circular brushes 66 will gather the liquified material from the periphery of the roller 40.

For each brush 66, a suitable supply package of yarn or thread 68 is provided, said packages each being mounted on a suitable spindle 70, extending upwardly from the floor 71. After the strand 27 is drawn from the package 68 it passes through a suitable eyelet 72 on a horizontally disposed bar 73. This bar is U-shaped and has its ends attached to bearings 42 and 43. From the eyelet 72 the strand 27 passes through an elongated eyelet 74 in the free end of a wire 75, said wire 75 extending from a plate member 76 which in turn is pivoted as at 77 to downwardly extending bolt 78. The upper end of the bolt 78 is supported by the upper portion of the framework 10. The position of the eyelet 74 (Figures 1 and 2) is such that the strand 27 will be held in

contact with the outer walls of the bristles of brush 66. Therefore, as the brush rotates the bristles of the brush will apply the solution 55 to the strand. After leaving the brush 66 the strand 27 passes through a second eyelet 79 on transverse bar 80. This traverse bar has its ends mounted for reciprocation in brackets 82 and 83 on the framework 10. The traverse bar 80 has a downwardly extending arm 85 integral therewith and the lower end of this arm is adapted to fit in a suitable groove 86 of hub member 87. The shape of the groove is such that as the shaft 41 rotates, oscillation will be imparted to the arm 85 and traverse bar 80 to thereby cause the strands 27 to move back and forth longitudinally of the shaft 63 across the peripheries of brushes 66. In this manner all portions of the brush peripheries will be used for applying the treating material 55 to the strand, as the strand will be rolled over the brush as it is moved from one side of the brush to the other side thereof. A suitable tension spring 89 is provided between members 65 and 85 in order to stabilize the lower end of the arm 85 and to hold it securely against one side of groove 86 at all times. Also an extension 90 having an elongated slot 91 therein, is provided for holding the arm 85 and the traverse bar 80 in its proper path during reciprocatory movement, said extension being an integral part of bracket 83.

When material such as wax or paraffin is used, it is necessary to reduce the same to a liquified state, so that a very small layer will adhere to the roller 40 as it rotates therein. Immediately after the liquified material has been transferred from the roller 40 to the bristles of brush 66 it assumes a semi-hardened state. Since the material transferred from the roller 40 to the brush 66, is in a mushy state, it may be applied easily and uniformly to the periphery of the strand 27 as it passes over the brush. The rotative movement of the brush will not only apply the wax material to all portions of the strand periphery but at the same time tend to parallelize all of the projecting fibers, because the brush is rotating constantly in one direction. In addition to making a uniform application of the material and parallelizing the fibers, a very fine polish is imparted to the yarn because the material is gradually approaching a congealed or solid state, after leaving trough 30.

Strand control mechanism

It is very essential that the strand 27 be withdrawn from contact with the brush immediately upon the stoppage of the winding machine. In order to stop the winding machine, the lever 23 (Figures 1 and 3) is turned in a counterclockwise manner so that the tightener pulley 18 will be raised out of contact with the belt 17. At this time, it is necessary that the strand 27 be withdrawn from contact with the brush as stated above, to prevent an excess amount of treating material adhering and solidifying upon the periphery of the strand and thus causing an enlarged portion on the strand. This withdrawal of the strand is effected by means of a suitable arm 96, extending laterally from the lower portion of handle 23. The free end of arm 96 has a downwardly extending link 97 pivoted thereto, and the lower end of the link is pivoted as at 98 to the plate member 76. When the handle 23 (Figure 1) is rotated from bold line position to dotted line position, the arm 96 and link 97 will be raised thus raising the free end of wire 75 and

its associated eyelet 14 from bold line position to dotted line position in Figure 2 to thereby hold the strand out of contact with the brush 66. At the same time the tightener pulley 18 will be raised to stop the rotation of package 14.

Figure 4 shows a slightly modified form of the invention in which like reference characters will apply to like parts and a description will be made only of the parts which differ. The specific modification shown is particularly adapted for use when applying size material to strands of yarn. In this form, a trough 100 is provided having a compartment 101 between its inner and outer walls. This trough has a roller 102 rotatably mounted therein upon which is mounted a second roller 103. It will be noted that the lower roller 102 is adapted to be partially immersed in a size solution 104. When the strand 21 is drawn from the package 68 it passes upwardly over a roller 107 and then downwardly beneath and around the lowermost roller 102 where it is subjected to the size solution. The strand then passes upwardly around the right hand periphery of roller 103 and then in a substantially horizontal position between squeeze rollers 110 and 111, where any excess of size is squeezed from the strand. The strand then passes upwardly and into contact with a suitable drying agent such as a steam pipe 112 so that the strand will be partially dried. After being partially dried, the strand is then passed through a suitable rotating brush 114 on shaft 115, after which it passes upwardly through eyelet 19 on traverse bar 80, then through tension device 29 and onto package 14.

By first immersing the strand, then squeezing the excess moisture out of the strand, then partially drying the same to reduce the moisture content of the size on the strand, and then brushing the periphery of the strand and the size while still moist, it is possible to obtain a parallelization of the projecting fibers on each strand and to also add a fine polish thereto.

In the drawings and specification, these has been set forth a preferred embodiment of the invention, and although specific terms are employed, they are used in a generic and descriptive sense only and not for purposes of limitation, the scope of the invention being set forth in the following claims.

I claim:

1. Apparatus for treating thread with molten paraffin, comprising means for rotating a package of thread to wind a strand thereon, a rotary brush, means for applying molten paraffin to said brush, means for passing said strand in contact with said brush to thereby cause said material to be transferred to the thread and means auto-

matically operable upon the stopping of said package rotating means for moving said thread out of contact with the brush.

2. Apparatus for treating thread with paraffin, comprising a container for holding the paraffin, means for heating said container, a rotating roller in said container and adapted to be partially immersed in said liquid paraffin, a rotary brush having peripheral contact with a portion of the roller not immersed, means for passing a thread in contact with said brush to thereby cause the paraffin to be transferred to the thread.

3. Apparatus for treating thread with paraffin, comprising a container for holding said paraffin, means for heating said container, a rotating roller in said container and adapted to be partially immersed in said liquid paraffin, a rotary brush having peripheral contact with a portion of the roller not immersed, means for passing a thread in contact with said brush to thereby cause the paraffin to be transferred to the thread and means automatically operable upon the stopping of said thread passing means for moving the yarn out of contact with said brush.

4. Apparatus for applying a solid lubricant to thread which comprises means for winding thread onto a package, means for stopping rotation of the package, a trough for holding the lubricant, means for heating the trough to render the lubricant into a liquid state, a roller mounted for rotation in the trough and in contact with the liquid lubricant, means for rotating the roller, a rotary brush in contact with the roller, means for holding the thread in contact with the brush and means operable by stoppage of rotation of the thread receiving package for moving the holding means to move the thread out of contact with the brush.

5. Apparatus for applying a solid lubricant to thread which comprises means for winding thread onto a package, means for stopping rotation of the package, a trough for holding the lubricant, means for heating the trough to render the lubricant into a liquid state, a roller mounted for rotation in the trough and in contact with the liquid lubricant, means for rotating the roller, a rotary brush in contact with the roller, means for holding the thread in contact with the brush, means operable by stoppage of rotation of the thread receiving package for moving the holding means to move the thread out of contact with the brush, and means for moving the thread longitudinally of the brush to thereby roll the thread across the brush to insure that all portions of the thread are subjected to the lubricant.

GEORGE C. DAVIS, JR.
